UNITED STATES PATENT OFFICE.

OSCAR O. NYGAARD, OF SAUGUS, MASSACHUSETTS, ASSIGNOR TO COMBUSTION ENGINEERING CORPORATION, OF NEW YORK, N. Y., A CORPORATION OF NEW YORK.

STOKER AIR CONTROL.

Application filed March 23, 1923. Serial No. 627,065.

My present invention relates to stokers, and more particularly to an improved method of and apparatus for distributing and regulating the flow of air to the fuel bed in automatic stokers.

In stocking apparatus, and particularly in automatic stoking apparatus of the types in use at the present day, and with the type of fuel necessarily employed therewith, it becomes essential for a proper economical working of the apparatus to provide oxygen containing fluid, such as air, to the fuel bed in proportion to the depth of fuel in the bed at any point throughout the length thereof, and in the past, although many attempts have been made to devise means for regulating the amount of air to the fuel bed, all such devices have failed to function properly as they operated over too great an area of the stoker. A great many automatic stokers are made extremely large and the tendency is for such units to become larger and larger as time goes on with the result that the difference in the depth or thickness of the fuel bed on the grate at the receiving or inlet end and at the dumping or exit end thereof is continually increasing.

An average depth of fuel bed particularly in underfeed stokers is at present from thirty to thirty six inches at the receiving end and from six to eight inches at the dumping end of the grate. It is evident that a fuel bed thus proportioned should not be supplied with an equal quantity of air at all points therein, nor with air of the same pressure and velocity as such air would bypass the thick portion of the fuel bed and burn holes in the thin portion of the fuel bed.

Previous practice has been to use an amount of air and of a pressure suitable to a point in the fuel bed about half way between the thickest and the thinnest portions of the same and depending on a very high distance between the surface of the fuel bed and the lower rows of tubes or heating surface of the boiler for a complete mixture and combustion of the gases generated.

This practice has necessitated a great outlay of money for very high boiler settings and the necessary building or housing surrounding such setting. It will be possible by the use of my method of distributing and regulating the air to the fuel bed in quantities, pressures and velocities in accordance

with the thickness of the fuel bed, to make such excessively high and expensive boiler settings unnecessary, in that I am enabled to supply the right amount of air to every point in the fuel bed, thus forming the right mixture of gases in the fuel bed which assures complete combustion of the fuel in, at, or near the surface thereof, instead of depending as in previous practice on a long travel of the gases to assure mixing and complete combustion before they become chilled through contact with the heating surface of the boiler.

Another feature of my invention is that, should the fuel bed burn through at any particular point, or the tuyères fail to operate at any particular point, or the fuel feeding means for any particular fuel trough fail to operate, whereby fuel in such trough would very quickly burn out and allow excess air to enter the furnace, I have provided novel means whereby the air to such burned out portions can be regulated or completely shut off at will and local faults quickly remedied.

An underfeed stoker is usually made up of several units or fuel troughs spaced in position side by side and several units may be operated from a common driving means. When the driving means fails to operate or any one of the units fails to function, the bypassing of the air through such unit or several units is so severe that it has been found necessary to shut down and discontinue the operation of the whole furnace and boiler.

In my method of distributing air to the fuel bed I regulate the air flow to each row of tuyères or units independently from any other unit; thus, should any unit or any part of the unit become disabled I have ready means to regulate or shut off such unit from the air supply and thereby maintain the rest of the furnace in economical operation. None of the devices in use at the present time provide means for overcoming the difficulty of local faults and while they have been successful in admitting the air to the fuel bed, considering the fuel bed as a unit, they have not been successful in curing local faults or of being able to shut down or shut off the supply of air to a disabled fuel trough while permitting the feeding of air to the remaining good fuel troughs. So far as I am aware,

also, there have been no means devised whereby the air supplied to the fuel bed throughout the length of the trough is proportioned to the depth of the fuel at any point along the length of the trough nor have there been any means devised for altering or regulating the amount of air delivered at any point along the fuel troughs.

In my present invention I have obviated the objectionable features above noted and have designed an air feeding means in which the air to each fuel trough is supplied from a common pressure or wind chamber and in which the air supplied to each trough separately may be regulated as regards amount and velocity according to the depth of fuel at any point along the length of the trough and means are associated with such mechanisms for varying the amount of air supplied. I have arranged the air controlling means for each trough independent of every other unit in the stoker and may control the admission of air to the trough from no air at all to full flow of air and am thus enabled to completely shut off the supply of air to any trough or row of tuyères should the fuel supply means for such trough fail to function or should a localized burning out occur, I may shut off the supply of air to this particular trough, thus putting the same out of commission while yet retaining the fuel troughs of the rest of the stoker in commission.

My invention is applicable to any of the existing forms of automatic stokers employing the usual form of tuyères and in the showing of my invention I have illustrated the applicability of the same to the various forms of tuyères and it is to be understood that my invention is not limited to the form of tuyère that may be employed or to the type of stoker apparatus that may be employed, but is applicable to any form of fuel burning apparatus wherein a fuel bed is employed and to which it is necessary to admit air for the proper consumption of the fuel.

In the accompanying drawings,

Fig. 1 is a sectional side elevation through the center of a row of tuyères showing my invention associated therewith;

Fig. 2 is a sectional elevation on the line 2-2 of Fig. 1; and

Fig. 3 is a detail showing the means for regulating the throw of the air admission means.

Referring to the drawings, 10 designates a foundation on which is mounted the spaced fuel troughs 11 constituting supports for the tuyère blocks, and 12 designates a portion of the brick masonry enclosing the stoker apparatus, a channel iron 13 extending across the furnace and acting as a support for the front end of the fuel troughs 11, a plate 14 enclosing the space extending

between the side walls 85 and the base 10 and channel iron 13. Between adjacent fuel troughs and on the upper edge of such adjacent troughs is placed a plurality of tuyères 15, 16, 17, 18, or any other desired form of tuyère block that may be available. The tuyère blocks, base, and apparatus just described form practically a wind or pressure chamber 19, and extending upward through the base 10 is an air supply pipe 20 provided with a damper 21 operated in the usual manner and by means of which the supply of air to the wind or pressure chamber is controlled.

Referring now particularly to Figs. 1 and 2, it is assumed that the form of tuyère block designated by 15 has been employed, which tuyère block consists essentially of a substantially semi-cylindrical fuel support 22 resting on, and spanning, the space between adjacent troughs 11, such fuel supports being provided with a plurality of orifices 23 through which air may flow and with a floor plate 24, the distance between floor plates, as clearly shown in Fig. 1, constituting a passage extending from the air pressure chamber 19 to the orifices 23. Pivoted to the sides of the troughs 11 and substantially midway between adjacent floor plates 24 by bolts 25 are downwardly extending members 26 at the upper ends of which and formed integrally therewith is a right angled plate 27, the length and breadth of this member 27 being substantially equal to the area defined by adjacent floor plates 24 and the sides 84 of tuyères 15. It is obvious, therefore, that, if the member 27 is swung on its pivoting bolt 25, the plate 27 may be swung into such a position as to completely shut off the flow of air to the orifices 23 of any tuyère block 15, and it is understood that there is one such plate 27 for each of the tuyère blocks 15. The downwardly extending members 26 are each provided with a slot 28. A bar 29 substantially equal to the length of the inclined arranged tuyère blocks 15 is provided at intervals with bolts 30 each of which bolts extends through the slot 28 on the downwardly extending members 26, the position of the bar 29 with relation to its slot being adjustable while the bolts 30 are arranged to be rotatably mounted in the bar 29. By this means movement of the bar 29 causes a rotative movement of the members 26 about their pivot bolts 25 and, therefore, a corresponding movement on the part of the plates 27 with respect to the tuyère blocks 15 and, therefore, such structure provided means for regulating the flow of air from the wind or pressure chamber 19 to the orifices 23 in the tuyère blocks 15. Secured to the bar 29 and intermediate the ends thereof is a stud 32 which passes through and is asso-

ciated with a slot 33 in a lever 34 that is secured to a shaft 35 rotatably mounted in pillow blocks 36 secured to the under side of the troughs 11. Secured to the shaft 35 at any convenient point along the length thereof is a downwardly extending lever 37 to the lower end of which is pivotally mounted one end of an operating bar 38 the other end of which extends through the wall 14 and is bent at right angles at 39 to provide a convenient handhold for an operator.

It is understood, of course, that there is a plate 27 for each of the tuyère blocks 15, and, in addition, I have arranged one such plates 27 for each of the overfeed grates 40. Also, the tuyère blocks 15 and the overfeed grates 40 are arranged in rows and by the construction above described I am enabled, by the manipulation of the operating rod 38, to move the plates 27 of each row of tuyère blocks and overfeed grates simultaneously. It should be understood, however, that I may provide a plurality of short shafts 35 and a plurality of operating levers 38 so as to make it possible to operate each of the rows of plates 27 individually thereby making it possible to control the admission of air to each row of tuyères 15 and overfeed grates 40 separately.

The contour of the fuel bed in the furnaces is indicated by the line 41 and the position of the bar 29 with respect to the slots 28 may be so arranged that the uppermost plate 27 will be opened to such an extent as to allow the maximum flow of air through the orifices 23 of the topmost tuyère block 15 in order to provide sufficient air for the combustion of the fuel in the trough, which fuel is thickest at this point, while the plate 27 in the lowermost tuyère block 15 or in the lowermost overfeed grate 40 will have a minimum opening, as shown in Fig. 1, as the fuel bed at this point is thinnest and the intermediate plates 27 will grade from the largest opening down to the smallest opening to provide air in predetermined amounts corresponding with the thickness of the fuel bed, this construction being clearly shown in Fig. 1. It will be understood that the position and throw of the lowermost and intermediate plates 27 may be varied in respect to the uppermost plate 27 by adjusting the bolt 30 in the slots 28. I may, in place of the construction above described; that is, arranging the bar 29 with relation to the slots 28 to carry out the object above described, make the depending portions 26 gradually increasing in length from the topmost one to the lowermost one when it will be noted that, with the bar 29 in the lowermost position of the slot 28, the same result as that described above will be attained. As another alternative to the construction above described, I may substitute for the down-

wardly extending member 26 with the integrally formed plate 27 thereof, a right angled plate 42, the downwardly extending portion of which is pivotally mounted at 43 to the sides of the troughs 11, and with the pivot point 43 as a center I provide in the downwardly extending portion of 42 an arcuate slot 44. Pivotally mounted on the pivot point 43 and extending downwardly therefrom is a lever 45 provided at its lower end with a longitudinally extending slot 46 that engages with the stud 32 in the bar 29, and associated with the arcuate slot 44 and passing through a perforation in the lever 45 is a threaded bolt 47 provided on its outer end with a wing nut 48 and by means of which the lever 45 and downwardly extending portion of 42 may be clamped together in adjusted position. Secured to the horizontal portion of the member 42 is a plate 49 equal in superficial area to the plates 27. By this construction the necessity of adjustment of the rod 29 with respect to the levers 45 or their equivalents, the downwardly extending members 26, for degree of opening of the plates 49 or 27 with respect to the adjacent floor plates 24 is dispensed with, it being possible by this method to individually adjust each plate 49 with respect to the adjacent floor plates 24 with which it is associated.

Various other forms than those described will suggest themselves to those skilled in the art and it is to be understood that my invention consists essentially in regulating the flow of air to a fuel bed of an automatic stoker, the amount of air being regulated in accordance with the thickness and requirements of the fuel bed at any particular point and I may accomplish this desirable result by means that may be adjusted from time to time so as to distribute the air over the entire fuel bed or over a predetermined portion of any of the fuel troughs or permanently arrange the controlling means.

While I have, therefore, necessarily described the preferred embodiments of my invention somewhat in detail, it is to be understood that I may vary in the size, shape, and arrangement of parts within wide limits without departing from the spirit of the invention.

Having thus described my invention, what I claim as new is:

1. In an automatic stoker, a fuel trough, tuyères in stacked relation along the length and at the sides of said trough, each tuyère having a floor plate, and adjustable means between adjacent floor plates for regulating the amount of air flowing through each tuyère.

2. In an automatic stoker, a fuel trough, tuyères in stacked relation along the length and at the sides of said trough, each tuyère having a floor plate, and means between ad-

jacent floor plates capable of being adjusted for regulating the flow of air through each tuyère.

3. In an automatic stoker, a fuel trough, an air channel at each side thereof, tuyères arranged in stacked relation on said channels, each tuyère including a floor plate and adjustable means associated with the floor

plate for determining the flow of air through each tuyère. ¹⁰

In testimony whereof, I have signed my name to this specification, at Boston, Massachusetts, this tenth day of March, A. D. 1923.

OSCAR O. NYGAARD.
